(57) **CLAIM**

The ornamental design for a docking station, as shown and described.

DESCRIPTION

FIG. 1 is a perspective view of a docking station showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a exploded partial enlarged perspective view thereof with the front of the device removed.

The broken line showing on the drawing disclosure is for illustrative purposes only and forms no part of the claimed design.
